UNITED STATES PATENT OFFICE.

FREDERIC H. BENDER, OF CHICAGO, ILLINOIS, ASSIGNOR TO AMERICAN STEEL
FOUNDRIES, OF CHICAGO, ILLINOIS, A CORPORATION OF NEW JERSEY.

RETAINING BOLT FOR SELF-CENTERING DEVICES.

Application filed August 4, 1924. Serial No. 729,922.

This invention relates to draft rigging supporting means, and more particularly to retaining means for self-centering devices.

The use of a self-centering device broadly is old. Heretofore, such devices have been mounted on carry irons in a manner tending to prevent displacement of the centering device with respect to the carry iron. For the most part such arrangements are generally successful except when a car is turned over, whereupon the self-centering device has been free to drop away from the carry iron and be lost.

One object of my invention is to provide simple, reliable and durable means for retaining a self-centering device in its proper operative association with the carry iron under both normal and abnormal circumstances.

Another object is to provide a simple and efficient combination of carry iron, self-centering device, and retaining means adapted to meet all of the requirements under conditions which are encountered in service.

These and other objects are accomplished by means of the arrangement disclosed on the accompanying sheet of drawings, in which—

Figure 1 is a front elevation of a striking casting having a carry iron integrally formed therewith, a self-centering device, and retaining means, a coupler shank being shown in section.

Figure 2 is a vertical longitudinal section al view taken in the plane of line 2—2 of Figure 1.

Figure 3 is a detail top plan view of the securing bolt forming a part of the invention.

The various novel features of the invention will be apparent from the following description and drawings and will be particularly pointed out in the appended claims.

Referring to the figures of the drawings, it will be noted that the invention is illustrated in connection with a striking casting 10 having integrally formed therewith a carry iron 11. A self-centering device including a carriage 12 is mounted upon rollers 13 supported by the carry iron 11 whereby the carriage 12 may have a transverse movement with respect to the carry iron 11 occasioned, for example, when the car to which the mechanism is attached is round ing a curve or encounters track irregulari-

ties. The carriage 12 automatically is made self centering by virtue of the fact that the rollers 13 are mounted between concave surfaces 14 and 15 on the carry iron 11 and carriage 12, respectively.

Under normal operating conditions the carriage 12 or self-centering device is prevented from moving into an inoperative position with respect to the carry iron 11 due to the fact that the carriage 12 is mounted down in between the transverse side walls 16 of the carry iron 11. However, entire reliance should not be placed upon the overlapping of the carriage 12 and side walls 16 of the carry iron 11 under all conditions to prevent displacement of the carriage 12 with respect to the carry iron, for it is apparent that under some circumstances, for example, when a railroad car is tipped over, it would be possible for the carriage or self-centering device 12 to be entirely disengaged from the carry iron 11 and lost. This will be particularly understood when it is realized that the degree of overlap between the carriage 12 and the side walls 16 is not as great as the clearance between the top interior wall 17 of the striking casting 10 and the top wall 18 of the coupler shank 19, which is mounted upon and supported by the carriage 12. This condition necessarily must exist to facilitate the assembly of the coupler and self-centering device within the striking casting 10, particularly where the carry iron 11 is formed integrally with the striking casting.

To retain the self-centering device within the striking casting under both normal and abnormal conditions, I have provided a retaining bolt 20, which extends vertically upwardly through vertically aligned openings 21 and 22 in the carry iron 11 and carriage 12, respectively, the upper end of the retaining bolt 20 having an elongated head or a head with oppositely extending ears 23, which ears normally extend transversely of the carriage 12, as shown in Figure 1, and occupy recesses 24 whereby the bolt 20 is prevented from downward displacement with respect to the carriage 12. The opening 21 in the carry iron 11 is elongated lengthwise of the carry iron as defined by the walls 25 to permit the carriage 12 to move laterally with respect to the carry iron 11. Also the opening 22 is elongated forwardly and rearwardly with respect to the

carry iron, as defined by the walls 26, to permit the head of the retaining bolt 20 to pass vertically therethrough when the ears 23 of the head are arranged in a position 5 90° from that shown in Figures 1 and 2. After the bolt 20 is passed vertically upwardly through the openings 21 and 22 to the extent that the ears 23 clear the top of the carriage 12, the bolt is given a rotative 10 movement through 90°, whereupon the ears 23 may move back and occupy the recesses 24, as hereinabove described. A washer 27 is placed on the retaining bolt 20, after which a key 28 is passed through an opening 29 near the lower end of the bolt 20 for normally retaining the bolt 20 against upward vertical movement beyond a predetermined point.

In this particular instance there is disclosed a well known type of coupler butt having a vertical enlargement 30 at the rear end. To apply and withdraw this coupler shank with the enlarged butt and still retain the overlapping relationship, after the parts 20 are assembled, between the carriage 12 and the walls 16 of the carry iron 11, the latter are cut away to provide aligned recesses 31. In assembling the parts, the coupler shank is first passed into the opening of the striking casting with the vertically enlarged 25 butt passing through the recesses 31. After the butt has passed inwardly beyond the striking casting, the carriage 12 is set in place on top of the rollers 13. Then the retaining bolt is passed vertically upwardly 30 through the openings 21 and 22 in the carry iron 11 and carriage 12 with the coupler shank elevated above the carriage 12 sufficiently 35 to permit the ears 23 to be lifted above the carriage 12 to permit rotation of the retaining bolt 20 through an angle of 90°, whereupon the ears 23 may drop back 40 into the recesses 24. The washer 27 and key 28 are then applied.

By means of this simple and durable arrangement the self-centering device or carriage 12 is retained in place under both normal and abnormal conditions and the parts are easily and quickly assembled and 45 disassembled in a manner to meet the various requirements.

I claim:

1. In draft rigging supporting means, a striking block having a carry iron, a self-centering carriage supported by said carry iron, a carriage retaining bolt connecting said carry iron and carriage and having an elongated head, said carriage having a bolt

receiving opening elongated in one direction for the passage of said elongated bolt 60 head, said opening having an offset recess for the reception of the elongated bolt head for locking said bolt against displacement in one direction, and means for preventing displacement of said bolt in another direction 65 whereby said carriage is locked against accidental displacement.

2. In draft rigging supporting means, a striking block having an integrally formed carry iron, a carriage supported by said 70 carry iron, a retaining bolt having an enlarged head and connecting said carry iron and carriage, said carry iron and carriage having elongated openings through which the retaining bolt passes to permit freedom 75 of movement of the carriage and bolt, said carriage having means cooperating with said elongated bolt head for retaining the bolt in position.

3. In draft rigging supporting means, a 80 striking block having an integrally formed carry iron, a self-centering device supported thereby, a retaining bolt for connecting said carry iron and self-centering device, said carry iron and self-centering device 85 having aligned openings for the reception of said bolt, and means for retaining said bolt in its operative position.

4. In draft rigging supporting means, a striking block having an integrally formed 90 carry iron with a middle recessed portion to permit longitudinal passage of a coupler butt, a carriage supported by said carry iron and having portions overlapping with relative raised portions of said carry iron 95 at either side of said recessed portion for normally preventing displacement of said carriage, and means for preventing displacement of said carriage under abnormal conditions.

5. In draft rigging supporting means, a striking block having an integrally formed carry iron with a middle recessed portion to permit longitudinal passage of a coupler butt, a carriage supported by said carry 105 iron and having portions overlapping with relative raised portions of said carry iron at either side of said recessed portion for normally preventing displacement of said carriage, and a vertically arranged retaining 110 bolt cooperating with said carry iron and carriage for preventing displacement of said carriage under abnormal conditions.

Signed at Chicago, Illinois, this 31st day of July, 1924.

FREDERIC H. BENDER.
